US0D1035039S

(12) **United States Design Patent** (10) **Patent No.:** **US D1,035,039 S**
(45) **Date of Patent:** **** Jul. 9, 2024**

(54) **RACK**

- (71) Applicant: **Meso Scale Technologies, LLC.**, Rockville, MD (US)
- (72) Inventors: **Aaron Leimkuehler**, Upper St Clair, PA (US); **Manish Kochar**, Rockville, MD (US); **Jennifer Parker**, Frederick, MD (US); **Nicholas Sammons**, Rockville, MD (US); **Bandele Jeffrey-Coker**, Darnestown, MD (US)
- (73) Assignee: **Meso Scale Technologies, LLC.**, Rockville, MD (US)
- (**) Term: **15 Years**
- (21) Appl. No.: **29/738,752**
- (22) Filed: **Jun. 19, 2020**

Related U.S. Application Data

- (60) Division of application No. 29/675,799, filed on Jan. 4, 2019, now Pat. No. Des. 889,685, which is a (Continued)

(57) **CLAIM**

The ornamental design for a rack, as shown and described.

DESCRIPTION

FIG. 1 is perspective view of a rack showing our new and ornamental design;

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The portions of the rack shown in broken lines shown in the figures attached hereto form no part of the claimed design.

1 Claim, 7 Drawing Sheets

Related U.S. Application Data

continuation-in-part of application No. 29/558,605, filed on Mar. 18, 2016, now Pat. No. Des. 882,818.
